COAXIAL TO WAVEGUIDE MODE-CONVERTING DUPLEXER EMPLOYING NONRECIPROCAL PHASE SHIFTING MEANS

Maurice E. Breeze, Huntington, N.Y., assignor to Sperry Rand Corporation, Great Neck, N.Y., a corporation of Delaware

Filed Oct. 25, 1961, Ser. No. 147,545
9 Claims. (Cl. 333—1.1)

This invention relates to a duplexing network for use between coaxial and uniconductor waveguides.

The well-known function of a duplexer in a microwave communication or radar system is to connect the transmitter to a radiating antenna and to isolate the receiver from the same antenna during the transmitting portion of the operation and to effect a reversal of said connections during the receiving portion of the operation so that only the receiver is connected to the antenna. Quite often the waveguide feeding the antenna is a coaxial transmission line in order to accommodate a rotary joint, while the transmission lines from the transmitting and receiving portions of the system are uniconductor waveguides such as rectangular waveguides. In the waveguide network joining the transmitter and receiver to the antenna, means must be provided for performing the usual duplexing operation and for converting the waves from TE₁₀ rectangular uniconductor waveguide mode to TEM coaxial waveguide mode. "Packaging" considerations usually require that these functions be performed with equipment which requires as little space as possible, and high power and frequency bandwidth operating requirements dictate that the equipment be as simple as possible so as to avoid excessive bends, twists, constrictions, obstructions etc. which usually limit the power handling and bandwidth capabilities of the system. Accompanying these requirements is the additional practical requirement that the network be relatively easy and economical to construct.

It therefore is an object of this invention to provide a high power and broadband waveguide network for performing a duplexing operation and for converting between rectangular uniconductor and coaxial waveguides.

Another object of this invention is to provide a coaxial-to-uniconductor waveguide transition which is compatible with, and forms part of, a duplexing network.

Another object of this invention is to provide a relatively compact and simple waveguide network for performing a duplexing operation and for converting the transmission line from uniconductor to coaxial waveguides.

Another object of this invention is to provide a waveguide network for performing a duplexing operation utilizing unidirectional phase shifting elements, and to accomplish highpower broadband mode conversion from uniconductor to coaxial waveguide by utilization of the phase relationships established in the duplexing operation, hence achieving both mode conversion and duplexing functions with a minimum of network complexity.

In accordance with this invention, the mode-converting duplexer is comprised of a uniconductor waveguide hybrid junction such as a magic tee or 3 db directional coupler. Differential phase shifting means are coupled to at least one terminal of a pair of terminals of the hybrid so that the waves propagating in two uniconductor waveguides toward the coaxial waveguide are 180° out of phase with each other, and the difference in phase shift in the two waveguides for opposite directions of wave propagation is 180°. The rectangular waveguides coupling the two adjacent terminals of the hybrid are physically positioned contiguous each other with a common

2

board wall therebetween, and an axially-aligned transition section joins the contiguous uniconductor waveguides to a coaxial waveguide. The common broad wall of the uniconductor waveguide tapers into the center conductor

5 of the coaxial line, and the waves in the two uniconductor waveguides being 180° of the phase join on said center conductor to propagate in a TEM mode in the coaxial waveguide. In the reverse direction of propagation, waves propagate from the coaxial line to both the uniconductor waveguides and in passing through the differential phase shifter the phase relationship between the two waves is altered so that they combine in the hybrid junction to propagate from an output terminal that is different from the input terminal of said junction.

15 The present invention will be described by referring to the accompanying drawings wherein:

FIG. 1 is an isometric illustration, partly broken away, showing an embodiment of the invention using a common broad wall hybrid directional coupler;

20 FIG. 2 is a series of cross-sectional views at different positions along the structure of FIG. 1 illustrating the electric field patterns at the respective cross sections;

FIG. 3 is an alternative embodiment of the invention wherein the hybrid junction is a common narrow wall hybrid directional coupler;

25 FIG. 4 is a series of cross-sectional views taken at different positions along the structure of FIG. 3 illustrating the electric field patterns at the respective cross sections;

FIG. 5 is an embodiment of the invention similar to 30 the embodiment of FIG. 1 wherein the hybrid junction is a folded E-plane magic tee;

FIG. 6 is a series of waveforms illustrating the propagating waveforms at different places in the device of FIG. 5;

35 FIG. 7 is another embodiment of the invention employing a folded H-plane magic tee hybrid junction, and;

FIG. 8 is a series of waveforms illustrating the propagating waveforms at various places in the device of FIG. 7.

40 Referring now to FIG. 1 of the accompanying drawings, the mode-converting duplexer is comprised of a broad wall hybrid directional coupler 10 which in turn is comprised of a top and bottom adjacent waveguides 11 and 12 which have a common broad wall therebetween.

45 Said directional coupler has one pair of terminals 13 and 14 which may be coupled respectively to the receiver and transmitter, and a second pair of terminals 15 and 16 which respectively are coupled to differential phase shifting sections 21 and 22. Coupling between waveguides

50 11 and 12 is accomplished in hybrid coupler 10 by means of coupling slots 18 and 19 in the common broad wall. Hybrid coupler 10 may be the type described in U.S. Patent 2,833,933. It is the characteristic of this broad wall hybrid coupler that waves coupled into terminal 14 will

55 be divided evenly by coupling slots 18 and 19 and will propagate with equal magnitudes in primary and secondary waveguides 12 and 11. It is a further characteristic of the broad wall hybrid coupler that waves which propagate straight through the coupler in the primary waveguide will lag by 90° the coupled waves which are coupled into the secondary waveguide.

60 Differential phase shifting sections 21 and 22 are the type now well known in the art, and for use in the rectangular uniconductor waveguides illustrated in FIG. 1 will take the form of a transversely magnetized ferrite element asymmetrically positioned in the waveguide. This type of phase shifter is discussed on page 52 and elsewhere in the January 1955 issue of the Bell System Technical Journal. The symbols used in FIG. 1 to denote these differential phase shifters now are common and indicate, for instance, that phase shifter 22 intro-

duces a 90° phase shift in waves propagating in the bottom guide with respect to waves propagating in the top guide for propagation from left to right in said waveguides. Similarly, differential phase shifter 21 provides the 90° phase shift of waves propagating in the top guide with respect to waves propagating in the bottom waveguide for propagation from right to left.

The top and bottom uniconductor waveguides 11 and 12 continue through phase shift sections 21 and 22 and are coupled to axially-aligned uniconductor-to-coaxial transition section 25 wherein the outer conductor 26 changes in shape from a square cross section at its left end to a circular cross section at its right end to form the outer conductor 29 of coaxial line section 30. Septum 27 at the left end of transition section 25 forms the common broad wall between waveguides 11 and 12 and then tapers in width throughout its length to form the center conductor 28 of coaxial line section 30. Coaxial line section 30 may be coupled to a rotary joint 32 to allow rotation of a coaxial waveguide antenna feed 33, this being a common arrangement in many radar systems.

In the operation of the mode-converting duplexer of FIG. 1, microwave energy from a transmitter is coupled into terminal 14, FIG. 2a, and divides evenly at the coupling slots 18 and 19 between primary waveguide 12 and secondary waveguide 11 with a phase relationship such that the waves that propagate toward terminal 16 lag by 90° the waves propagating toward terminal 15, as illustrated in FIG. 2b. The respective waves then pass through differential phase shifting sections 21 and 22 and the waves in bottom waveguide section 12 are delayed in additional 90° in phase by phase shifting section 22 so that said waves now are 180° out of phase with respect to the waves propagating in top waveguide 11, as illustrated in FIG. 2c. In passing through transition section 25 the waves propagate in a mode illustrated schematically in FIG. 2d, and upon reaching coaxial line section 30 propagate in a true TEM mode, FIG. 2e. Said waves then are coupled through rotary joint 32 to antenna 33 and are radiated therefrom.

In the received mode of operation, electromagnetic waves received by antenna 33 are coupled in the TEM mode through rotary joint 32 to coaxial line section 30, FIG. 2e, through transition section 25 in the mode illustrated in FIG. 2d, and into rectangular uniconductor waveguides 11 and 12 in the modes illustrated in FIG. 2c. The respective waves in the two waveguides then pass through differential phase shifting sections 21 and 22 wherein the waves in the top waveguide 11 are retarded in phase 90° with respect to the waves in bottom waveguide 12 so that the wave relationship between the respective waves is as illustrated in FIG. 2f wherein the waves in the top waveguide 11 are represented at an angle at -90° and the waves in the bottom waveguide 12 are represented at an angle of 180°. In passing through hybrid directional coupler 10 waves passing directly through top waveguide 11 are retarded an additional 90° in phase with respect to the waves in bottom waveguide section 12 so that they now have a total phase delay of 180° so as to combine in phase with the waves coupled into top waveguide 11 from bottom waveguide 12. These waves then continue on to the receiver which is not illustrated. On the other hand, waves coupled from top waveguide 11 into bottom waveguide section 12 are at an angle of -90° and the waves passing directly through bottom waveguide section 12 (at a phase angle of -180°) experience an additional 90° phase lag in passing through the coupling section and now are at a phase angle of -270° so that the direct waves in bottom waveguide 12 combine in destructive interference with the coupled waves from top waveguide 11 and the two will substantially cancel each other. Therefore, substantially all received waves will be coupled from antenna 33 to the receiver at terminal 13 and substantially none

of the waves will be coupled to the transmitter at terminal 14.

From FIG. 1 and the above description it will be seen that the operation of hybrid directional coupler 10, differential phase shifters 21 and 22 and transition section 25 are uniquely suited to duplex and simultaneously perform mode conversion between rectangular uniconductor waveguide and coaxial waveguide, inasmuch as the wave relationship established between waves in the various sections of the structure are utilized in both functions and have significance only in connection with the particular types of waveguides employed herein and the particular functions performed. It further may be seen that transition section 25 is an integral part of the duplexer inasmuch as duplexing operation can be accomplished with the device of this invention only with waves having the wave relationships established at said transition section 25.

An alternative embodiment of the mode-converting duplexer of this invention is illustrated in FIG. 3 which is similar to the embodiment illustrated in FIG. 1 with the exception that the hybrid coupler employed in FIG. 3 is a common side wall hybrid coupler 40 rather than the common top wall hybrid coupler 10 illustrated in FIG. 1. A distinction in the operation of these two couplers should be noted at this point. In the common narrow wall hybrid coupler, an example being the type described in U.S. Patent 2,739,287, the waves coupled into the secondary waveguide lag by 90° the waves which propagate directly through the primary waveguide. This relationship is just opposite to the relationship which exists in the common broad wall hybrid coupler used in the embodiment of FIG. 1.

In the operation of the embodiment of FIG. 3, waves from the transmitter are coupled into terminal 41, FIG. 4a, and propagate to the coupling region of hybrid coupler 40 wherein they divide equally between waveguides 43 and 44 with the wave relationship illustrated in FIG. 4b wherein the coupled waves in secondary waveguide 44 lag by 90° the direct waves in primary waveguide 43. In passing through differential phase shifting sections 45 and 46 the waves in waveguide section 44 will be retarded an additional 90° with respect to waves in waveguide 43 so that the waves in the two waveguides now are 180° out of phase with respect to each other, FIG. 4c. The two waveguide sections 43 and 44 then are bent so that they are aligned and share a common broad wall in the manner illustrated in FIG. 4d. Transition section 50 is substantially identical to transition section 30 of FIG. 1 and operates in the manner illustrated in FIGS. 4e and 4f to convert the waves into a TEM mode for propagation on coaxial line section 51.

In the received mode of operation the TEM mode waves propagate from coaxial line section 51, FIG. 4f, through transition section 50, FIG. 4e, and are coupled to rectangular uniconductor waveguides 43 and 44 to propagate therein in TE_{10} modes with a phase difference of 180° with respect to each other, FIG. 4d. In passing through differential phase shifting section 45 and 46, waves in waveguide 43 are retarded 90° so that the phase relationship between waves in the two waveguides is as illustrated in FIG. 4g. In passing through hybrid directional coupler 40 waves coupled from waveguide 43 into waveguide 44 experience an additional 90° phase retardation, a total of 180°, combine in phase with the direct waves propagating through waveguide 44 and propagate to the receiver. Waves coupled from waveguide 44 into waveguide 43 experience a 90° wave retardation, a total of 270°, and combine in destructive interference with the waves propagating directly through waveguide 43 and these waves substantially cancel. Thus, substantially all the received energy is coupled from terminal 53 to the receiver and substantially no energy is coupled from terminal 41.

The embodiment of the invention illustrated in FIG.

5 is similar to the embodiment illustrated in FIG. 1, one difference being that a folded E-plane magic tee hybrid junction 55 is employed instead of the hybrid directional coupler 10 in FIG. 1. An additional distinguishing feature is that the differential phase shifter 56 introduces 180° additional phase difference between the waves propagating from right to left in uniconductor waveguides 58 and 59. No phase shift is introduced to waves propagating in the opposite direction in the two waveguides. The structure to the right of differential phase shifter 56 is substantially identical to the structure to the right of differential phase shifter 22 of FIG. 1, consequently further description of this additional structure is unnecessary. The folded E-plane hybrid junction of FIG. 5 is of the type described and claimed in U.S. Patent 2,853,683.

In the operation of the mode-converting duplexer of FIG. 5, waves from a transmitter are coupled into terminal 60 with the polarity indicated thereat, are coupled into junction 55 and are coupled with equal magnitudes into waveguides 58 and 59 with the polarities illustrated in FIG. 5. These waves propagate through the transition system onto the coaxial line section in the manner discussed in connection with FIG. 1. In the receive mode of operation, waves propagate from the coaxial line section, through the transition section and into rectangular uniconductor waveguides 58 and 59 with the relationship illustrated in FIG. 6a. In passing through differential phase shifter 56, the waves in the lower waveguide 58 experience a 180° phase shift so that the relationship between the waves in waveguides 58 and 59 now are as illustrated in FIG. 6b. These waves combine in phase in the junction of magic tee 55 and propagate substantially exclusively to terminal 62. Terminal 60 is substantially isolated from the received waves because of the operation of the folded E-plane magic tee. Thus duplexing operation together with mode conversion between rectangular uniconductor waveguides 58 and 59 and the coaxial waveguide has been accomplished.

A further embodiment of the invention is illustrated in FIG. 7 which is similar to the embodiment illustrated in FIG. 3, with the exception that a folded H-plane magic tee hybrid junction 70 is employed in the place of narrow wall hybrid directional coupler 40 in FIG. 3. Further, a 180° differential phase shifter 71 is employed in FIG. 7 to establish the correct wave relationships for duplexing between waves propagating in waveguides 74 and 75. The folded H-plane magic tee hybrid junction 70 may be of the type described in U.S. Patent 2,840,787. The portion of the mode-converting duplexer of FIG. 7 which is to the right of differential phase shifter 71 is substantially identical to the corresponding portion in FIG. 3 and will not be further explained inasmuch as the operation is identical.

In the operation of the device of FIG. 7, waves from a transmitter are coupled to terminal 77 with the polarity indicated thereat, and are coupled through the junction to uniconductor waveguides 74 and 75 with the relative polarities indicated in FIG. 8a. Differential phase shifter 71 has no effect on the waves propagating in the waveguide 75 so that the waves will continue to propagate in waveguides 75 and 76 and will combine in the TEM mode in the coaxial line section in the manner described in connection with FIG. 3. In the received mode of operation, waves are coupled from the coaxial waveguide, through the transition section into waveguides 74 and 75 in the manner previously described in connection with FIG. 3. Upon encountering differential phase shifter 71 the waves in waveguide 75 will be shifted in phase by 180° and the waves in waveguides 74 and 75 will be in phase with respect to each other, as illustrated in FIG. 8b. These waves combine in folded H-plane magic tee hybrid junction 70 and propagate from terminal 89 to the receiver. Because of the operation of the junction, substantially none of the received waves are coupled to terminal 77. Again, it is obvious that a du-

plexing operation and a simultaneous conversion of propagating modes has been achieved.

It now should be apparent that the axially-aligned arrangement of the hybrid junction, differential phase shifter and transition section provides a relatively simple, compact, broadband and relatively high power device for performing the dual function of duplexing and mode conversion between rectangular uniconductor waveguide and coaxial waveguide.

10 While the invention has been described in its preferred embodiments, it is understood that the words which have been used are words of description rather than of limitation and that changes within the purview of the appended claims may be made without departing from the true scope and spirit of the invention in its broader aspects.

15 What is claimed is:

1. A waveguide network for performing a duplexing operation between uniconductor and coaxial waveguides, comprising the combination of a uniconductor waveguide 20 hybrid junction having two pairs of terminals, waves coupled into either one of the terminals of the first one of said pairs of terminals dividing equally and propagating from both terminals of the second pair of terminals, two adjacently-positioned uniconductor waveguides 25 having a common broad wall therebetween respectively coupled to the terminals of said second pair of terminals, differential phase shifting means coupled between at least one of the terminals of said second pair of terminals and its respective adjacently-positioned uniconductor waveguide, the electrical distance from a first terminal of said first pair of terminals to a first one of said uniconductor waveguides being 180° longer than the electrical distance to the other one of said uniconductor waveguides for waves propagating in one direction and 30 the electrical distance from the second terminal of said first pair of terminals to the other one of said uniconductor waveguides being 180° longer than the electrical distance to the first one of said uniconductor waveguides for waves propagating in the opposite direction, and a 35 uniconductor-to-coaxial waveguide transition section coupled to the end of said two uniconductor waveguides, said transition section having a center conductor coupled to the common broad wall of said two uniconductor waveguides and tapering in width throughout its 40 length substantially to the dimensions of a center conductor of a coaxial waveguide.

45 2. The combination claimed in claim 1 wherein said hybrid junction is a common broad wall directional coupler having primary and secondary waveguides and wherein said phase shifting means are coupled to both terminals of said second pair of terminals and produce 90° differential phase shift in waves propagating in the primary waveguide with respect to waves propagating in the second waveguide for propagation in one direction and introduce 90° differential phase shift of waves propagating in the secondary waveguide with respect to waves in the primary waveguide for propagation in the opposite direction.

50 3. The combination as claimed in claim 1 wherein said hybrid junction is a common narrow wall directional coupler having primary and secondary waveguides and wherein said phase shifting means is coupled to both terminals of said second pair of terminals and produce 90° differential phase shift in waves propagating in the secondary waveguide with respect to waves in the primary waveguide for propagation in one direction and introduces 90° differential phase shift in waves propagating in the primary waveguide with respect to waves propagating in the secondary waveguide for propagation in the opposite direction.

55 4. The combination claimed in claim 1 wherein said hybrid junction is a folded E-plane magic tee and wherein said phase shifting means is coupled to only one terminal of said second pair of terminals and introduces 70

180° differential phase shift in waves propagating in one waveguide.

5. The combination claimed in claim 1 wherein said hybrid junction is a folded H-plane magic tee and wherein in said phase shifting means is coupled to only one terminal of said second pair of terminals and produces 180° differential phase shift in waves propagating in one waveguide.

6. An axially-aligned waveguide network for performing a duplexing operation between uniconductor and coaxial waveguides comprising the combination of a uniconductor waveguide hybrid junction having two pairs of terminals, waves coupled into either one of the terminals of the first one of said pairs of terminals dividing equally and propagating from both terminals of the second pair of terminals, two adjacently-positioned uniconductor waveguides having a common broad wall therebetween and respectively coupled to said second pair of terminals, uniconductor waveguide differential phase shifting means coupled between at least one of the terminals of said second pair of terminals and its respective adjacently-positioned uniconductor waveguide, the differential phase shift introduced to waves propagating in opposite directions through said phase shifting means being 180°, and an axially-aligned uniconductor-to-coaxial waveguide transition section coupled to the end of said two uniconductor waveguides, said transition section having a center conductor coupled to the common broad wall of said two uniconductor waveguides and tapering in width throughout its length substantially to the dimensions of a center conductor of a coaxial waveguide.

7. A mode-converting duplexer coupled between a coaxial waveguide and two uniconductor waveguides comprising a uniconductor waveguide hybrid junction having two pairs of terminals, said junction operating to divide equally between two terminals of one pair of terminals the waves coupled into one terminal of the other pair of terminals, a pair of uniconductor waveguides sharing a common broad wall therebetween and respectively coupled to the terminals of said one pair of terminals, differential phase shifting means coupled between at least one of the terminals of said one pair of terminals and its respective adjacently-positioned uniconductor waveguide, the difference in electrical distance between the paths traveled by waves propagating in one direction between one terminal of said one pair of terminals and the two uniconductor waveguides being 180° and the difference in electrical distance between the paths traveled by waves propagating in the opposite direction between the other terminal of said one pair and the two uniconductor waveguides being 180°, a coaxial waveguide having inner and outer conductors, and a transition section between said coaxial waveguide and said two uniconductor waveguides, said transition section having an inner conductor which is connected to and tapered between the center conductor of said coaxial waveguide and the common broad wall of said two adjacently-positioned uniconductor waveguides.

8. A mode-converting duplexer for coupling between a coaxial waveguide and two uniconductor waveguides comprising a uniconductor magic tee hybrid junction having first and second pairs of terminals, the terminals of said hybrid junction being related so that waves coupled into either one of the terminals of said first pair of terminals will divide equally between the two terminals of the second pair of terminals, first and second rectangular uniconductor waveguides respectively coupled to the terminals of said second pair of terminals, said two

rectangular uniconductor waveguides being substantially aligned with respect to said hybrid junction and being adjacently-positioned at their ends opposite said hybrid junction with a common broad wall therebetween, differential phase shifting means coupled between at least one of the terminals of said second pair of terminals and its respective rectangular uniconductor waveguide, said phase shifting means cooperating with said hybrid junction to couple waves from one terminal of said first pair of terminals into the two rectangular uniconductor waveguides wherein the waves have a phase relationship of 180° with respect to each other, an axially-aligned uniconductor-to-coaxial waveguide transition means having one end coupled to said two adjacently-positioned rectangular uniconductor waveguides and having an inner conductor connected to said common broad wall and tapering along its length to a center conductor of a coaxial waveguide.

9. A mode-converting duplexer for coupling between a coaxial waveguide and two uniconductor waveguides comprising a uniconductor hybrid directional coupler having a first pair of adjacently-positioned terminals for coupling to said two uniconductor waveguides, first and second differential phase shifting means coupled respectively to each of a second pair of adjacently-positioned terminals of said directional coupler, said first differential phase shifting means introducing a 90° phase shift to waves propagating in a first direction with respect to waves propagating in the opposite direction and the second differential phase shifting means introducing a 90° phase shift to waves propagating in said opposite direction with respect to waves propagating in said first direction, two axially-aligned rectangular uniconductor waveguide means coupled through said phase shifting means to said second pair of adjacently-positioned terminals of said directional coupler, said two rectangular uniconductor waveguides being adjacently positioned at their ends opposite said directional coupler and having a common broad wall therebetween, said phase shifting means cooperating with said directional coupler to couple waves from one terminal of said first pair of terminals into the respective rectangular uniconductor waveguides with a phase relationship of 180° with respect to each other, an axially-aligned uniconductor-to-coaxial waveguide transition means coupled at one end to said two adjacently-positioned rectangular uniconductor waveguides and having an inner conductor connected to said common broad wall and tapering along its length to a center conductor of a coaxial waveguide, and an axially-aligned coaxial waveguide coupled to the opposite end of said transition section, whereby waves coupled to one terminal of said first pair of terminals propagate through said directional coupler, through said phase shifting means and said transition section and combine to propagate in said coaxial waveguide in a TEM mode.
